5 Claims. (Cl. 52—283)

ABSTRACT OF THE DISCLOSURE

Structure of the type disclosed in copending application Ser. No. 309,777, with one or more profiled columns supporting a slab composed of triangular plates, the present improvement residing in the provision of a column composed of complementary, rigidly interconnected vertical profile members of constant horizontal cross-section serving as anchorages for the slab plates and for adjoining walls.

This application is a continuation-in-part of copending application Ser. No. 309,777 filed Sept. 18, 1963.

My present invention relates to an improved structural assembly for the erection of polygonal structural units having, for example, vertices defining between them angles of, say, 60° as more generally described in my copending application mentioned above.

In the aforementioned copending application, I have observed that prefabrication of units to be assembled into building structure has been characterized hitherto by a limited variation in style and adaptability to unusual environments. To overcome these disadvantages, I have provided prefabricated units and structural elements which incorporate substantially horizontal slabs composed of polygonal, more specifically triangular, plates bearing edgewise upon one another so as to define a floor, roadway or platform of polygonal outline, in combination with means rigid with certain of these plates for supporting the slab and/or holding the plates together. Thus, I have found the use of triangular plates to be highly advantageous since, as observed in application Ser. No. 309,777, they represent the smallest building blocks capable of being assembled into continuous geometrical figures of unlimited width and length. The triangular plates can be grouped into square, rectangular or hexagonal subunits which, in turn, can be disposed contiguously to expand the structure in rectangular, hexagonal or modified configuration. For this purpose it is convenient to employ triangular slabs whose vertices include angles which are aliquot parts of 180°, such as isosceles right triangles or equilateral triangles. Moreover, the slabs are rigidly joined to associate upright members such as walls, columns or other supports with the aid of frames or brackets matingly engaging suitably profiled peripheral portions of the polygonal plates. Special connectors are secured to the slabs for holding their plates together, e.g. in form of a polygonal insert matingly engaging complementary recesses in these plates, preferably at the junctions of the vertices of several triangular plates together constituting a rectangular or hexagonal subgroup. In that application, I have also stressed that the columns joined to the slab may be of the configuration of the subgroup and can serve as a connecting member at the junctions of the vertices of several plates. These columns may be solid or tubular and may serve as casings for a variety of utility ducts such as gas, water and drain pipes or electric cables. Thus, floor and roof structures can be formed of polygonal outline with wall means rigid with the floor

2

and/or roof structure extending along edges of the polygonal slabs.

While slab and roof constructions of this character have been found to be of significant advantage in structures which can be effectively erected with prefabricated units because of the versatility of the configuration of the slabs, it is also desirable to use a similar approach in the prefabrication of room units, chambers or the like in which the walls adjoin angularly in the manner of cells and are supported by uprights. Partition assemblies using columns and upright frames to which wall panels are secured have been used widely to subdivide existing structures or to develop and expand such structures. In addition they have been employed for the erection of prefabricated industrial and domestic structures. Such conventional frame, panel and column assemblies require the walls of adjoining units to be at right angles to one another and thus substantially limit the versatility of construction.

It is, therefore, the primary object of the present invention to extend the principles originally set forth in my application Ser. No. 309,777 to prefabricated room units having upright columns and to permit the rapid assembly of prefabricated structures with greater versatility than has been possible heretofore.

Another object of this invention is to provide a column or post structure for prefabricated units which will facilitate the building-block-type erection of a multi-unit structure with ease and at low cost.

These objects and others which will become apparent hereinafter are attainable, in accordance with the present invention, through the provision of a composite column of at least partially closed cross-section made up of a plurality of angularly adjoining contiguous members extending the full length of the column and having connecting formations including angles of substantially 60° with one another, bolts, rivets, or other fastening means being provided to secure the members rigidly together.

At least some of the angularly adjoining members making up each column are provided, in accordance with the present invention, with means—which may include the aforementioned connecting formations—for affixing horizontal elements to the columns at upper and lower portions thereof so as to constitute therewith frames for

panels or wall means, or supports for floor or ceiling slab structures, as set forth in my copending application mentioned above, with the walls including corresponding angles with one another. The horizontal traverses or beams may be constituted by metal profile bars or the slab arrangements of copending application Ser. No. 309,777 and, in the latter case, a column in accordance with the present invention will be provided at each of the vertices of a triangular slab structure. When profiles are used as structural members in place of triangular slabs, the columns are advantageously disposed at the vertices of an equilateral triangle with the profiles extending along the sides thereof. It has been found that the 60° included angle between the connecting formations of each column and the traverses spanning the columns while

including corresponding angles between them form a triangular unit which can be nested with other units or otherwise combined therewith to produce a grid-like arrangement characterized by great static strength. In a 60° grid in accordance with the present invention it has been found possible to span distances of up to 9 meters in two of the three dimensions of the grid while the third dimension is substantially unlimited. Advantageously, the horizontal traverses are profiles which lie in the plane of slab-type floor and ceiling arrangements with the profiles completely embedded in the horizontal slabs. Thus the profiles may be cast around with concrete or may serve as connecting members between triangular preformed slabs

70

which, along their junction, completely conceal the profiles; the connecting formations at the upper and lower ends of the column likewise are concealed in the floor or roof structures and thus are not visible from within the structural unit.

According to one aspect of the present invention, each or some of the vertical columns are of completely closed cross-section and are formed from six angularly adjoining and generally similar profiled members of channel construction whereby the arms of the channel members can be connected together with the members lying along sides of a hexagon. Similarly, the triangular plates can be equilateral triangles disposed about a column of this nature in hexagonal configuration so that corresponding vertices of the triangular plates bear centrally upon respective faces or channel members of the vertical column. A bearing member (e.g. of hexagonal cross-section) can be disposed centrally of these triangular slabs for affixing them to the column or fixedly positioning the slabs when a column is omitted. Alternatively, the column itself may, at its connecting formations with the horizontal slabs and/or profiled traverses, serve as a hexagonal bearing member. When the column is omitted at the center of one of the hexagonal units or subgroups, the center-bearing member may correspond in configuration to the column and indeed may be a column section whose connecting formations are secured to the traverse members and the triangular slab to tie them together in a star configuration at the center of the subgroup. In this manner, selective columns may be omitted in assembling the structure so that the floor and ceiling slabs can span relatively large distances without intervening uprights. The horizontal traverses and the profile members secured together to constitute the columns preferably are formed from aluminum or coated sheet or band steel (e.g. sheathed in a synthetic resin or zinc plated-galvanized for protection against discoloration and against corrosion).

According to a further feature of this invention, the arms of the channel-shaped column members may diverge from one another with an apex angle of substantially 60° and a half-angle of 30° while being connected together in contiguous manner such that the joined-together arms form connecting formations or flanges extending outwardly from the tubular core of the column. Alternatively, the arms of the channel members converge away from their bight portions with included angles of 60° and the channel members are connected along their adjoining arms to form inwardly directed flanges enclosed by the column shell. Again, these inwardly directed flanges can constitute the connecting members for the horizontal traverses even though they are concealed by the shell of the column formed by the closed array of the bights or webs of the channels. In this case, the bight portions or webs may be cut away to receive the horizontal traverses at the upper and lower ends of the columns or at an intermediate location therealong so as to form windows through which the horizontal traverses can be flanged or lapped against the flanges of the column. Moreover, the column should include at least two members whose connecting formations include an angle of 60° between them but may have one or more channel members or profiles whose connecting formations define complementary angles to a formation of another profiled column member whereby the two members can be joined together at right angles to support walls joining one another at 90° . Thus, a right-angle adapter can be formed by one type of profile member and have a flange or arm, corresponding to an arm of a 60° channel member as described above, which includes a 30° angle with the web of the profile and thus can be connected to the arm of a 60° channel to define therewith a right angle. Advantageously, the web of the channel members making up a hexagonal-section column can have a width of about 10 cm. whereby the column can be used to support walls and panel systems of such thickness that conventional

door structures, windows, shelves and cupboards can be maintained therein.

This arrangement permits the rapid assembly from pre-fabricated elements which can be modified on the construction site of structures for industrial and dwelling purposes with respect to both the outer shell and the interior wall arrangements. Essentially, for any structure, only the columns and horizontal traverses (profiles or triangular slabs) form the basic elements while the construction of the columns enables adaptation of the system to particular needs. All of the parts are standardized and can be interfitted as will be apparent hereinafter to enable rapid assembly of the system.

The above and other objects, features and advantages of the present invention will become more readily apparent from the following description, reference being made to the accompanying drawing in which:

FIGS. 1 and 2 are cross-sectional views through vertical columns of hexagonal configuration in accordance with the present invention;

FIG. 3 is a similar cross-sectional view through a column of triangular section;

FIGS. 4 and 5 are fragmentary perspective views illustrating the formations for attaching horizontal traverses to the channel members of the columns of FIGS. 2 and 3, respectively;

FIGS. 6 and 7 are cross-sectional views of vertical columns in accordance with this invention, illustrating how the basic channel members of the column may be used with angular adapters for right-angle connection of walls;

FIG. 8 is a cross-sectional view through a traverse beam adapted to span a pair of columns in accordance with this invention;

FIG. 9 is a perspective view of a skeleton structure in accordance with this invention; and

FIG. 10 is a diagrammatic perspective view of a horizontal slab arrangement adapted to be employed with the structural members illustrated in FIGS. 1-9.

In FIG. 1, I show a vertical column 1 (in cross-section) adapted to be used at the vertices of horizontal members of the type illustrated in the aforementioned copending application or at the vertices of structural sub-units of an upright frame or skeleton assembly as illustrated in FIG. 9 and described in greater detail below.

In accordance with the principles of this invention, the vertical column 1 is composed of 6 contiguous angularly adjoining channel-shaped profiles Ba of constant horizontal cross-section running the full length of the column and composed of aluminum (e.g. formed by extrusion) or steel sheet or bands.

The channel cross-section of the profile members Ba imparts a V-section to them with truncated vertices so that each channel has a flat upstanding web or bight portion 2 from which arms 3 in the form of vertical flanges extend. As indicated in FIG. 1, the arms 3 of each channel include respective apex angles α with one another, these angles being equal to 60° so that the half angles β of the arms 3 equal 30° . In this embodiment, the webs 2 lie along the sides of a hexagon and the arms 3 of adjoining channel members Ba are juxtaposed and parallel to one another so that they can be interconnected via rivets 4a, screw and nut connectors 4b or like fastening members inserted through aligned bores 4 in the juxtaposed arms 3 of the profiled members Ba. The rivets 4a and/or bolts 4b can be inserted at the construction site to permit assembly of the columns from the pre-fabricated members Ba as required or can be prefabricated entirely at a workshop for incorporation in the frame structure as will be described in greater detail hereinafter. The column, produced by joining the arms 3 of the profiles Ba at their connecting formations 4, thus constitutes a hexagonal shell (defined by the adjoining webs 2 and illustrated at S), this tubular shell constituting a duct or the like for utility purposes as illustrated in my copending application identified earlier. From the tubular

shell **S**, a plurality of angularly equispaced flanges **F**, defined by joining the juxtaposed arms **3** running the full length of the column, extend radially to the corners of a hexagon and serve to support horizontal traverses (e.g. profited beams or triangular concrete slabs) as will be apparent hereinafter.

In the modification of the column illustrated in FIG. 2, the profile members **Bi** making up the column have webs **7** which define a closed unit and lie along sides of a hexagon. The arms **6** of the channel-shaped profile members include with one another angles α of 60° and have respective half-angles β of 30° . As in the case of the column of FIG. 1, the arms converge toward the center of the hexagon and are juxtaposed with the arms of adjoining profile members **Bi** while having connecting formations in the form of registering bores **8** through which rivets **8a** or bolt assemblies **8b** can be inserted. The column **5** thus is of hexagonal section with a substantially larger enclosed area than that of FIG. 1 and can also serve as a duct for utility purposes. The six profile members **Bi** extending the full length of the column **5** are generally of U-section with the arms or shanks of the U turned inwardly toward one another so that the arms and web of each member **Bi** lie along three sides of a trapezoid. It will be apparent that the webs **7** form a shell **S'** which completely encloses and conceals the flanges **F'** formed by connecting the juxtaposed arms **6** of adjoining members **Bi**. Thus, the column **7** can be used in the interior of a structure and has no unsightly formations to interfere with the esthetic effect.

In FIG. 3, there is shown a modified column **9** whose six profile members **Bw** have juxtaposed arms **10** extending the full length of the column. The juxtaposed arms **10** have aligned connecting bores **13** by means of which the members **Bw** may be joined together via rivets or bolt arrangements as previously described and which form flanges **F''** to which the horizontal traverses and cross members may be connected. The arms **10** of each of the profile members **Bw** include angles α of, say, 60° with inwardly extending arms **12**. The arms **12** of adjoining profile members **Bw** are juxtaposed with one another and are formed with bores **13'** through which bolt and rivet assemblies may be inserted. The arms **10** and **12** of each profile **Bw** extend from respective webs **11** with the webs of the six angle members defining a closed column shell **S''** of triangular section which can serve as a utility duct and to which the cross members can be connected. The arms **10** are perpendicular (i.e. at right angles) to the respective web **11** while the arms **12** include respective angles $\beta=30^\circ$ with the latter. This arrangement provides a connection, in a skeleton using 60° subgroups, for connecting walls or support structures at right angles to each of the flanges of the hexagonal columns for which the column **9** may be substituted. In FIGS. 4 and 5, I show how the horizontal traverses may be connected to the respective profile or channel members **Bi** and **Bw** at the upper ends of the columns of FIGS. 2 and 3. Thus, the web **7** is cut away at **7'** in the channel member **Bi** of the column **5** to form a window **W** in to which the end of a channel **18a** (here constituting the horizontal traverses) can be inserted. The member **18** can be lapped against one of the projecting portions **6'** of the arms **6** flanking the window **W** and connected thereto via a bolt and nut assembly **18b**. The same assembly can be used for connecting the arms **6** at these projecting portions **6'** in tying the adjoining profile members **Bi** to one another. A similar window can be provided at the lower end of the member **Bi** or at any intermediate location therealong to permit corresponding traverse members to be secured to a respective arm **6** through a window. Similarly, a window **W'** (FIG. 5) is formed in the web **11** of the profile **Bw** of the column **9** (FIG. 3) so that a traverse (e.g. as shown at **18a** in FIG. 4 or at **18** in FIG. 8) can be affixed to the arm **12** or the arm **10** through this window at projecting portions **12'** and **10'**

5

flanking the window. The windows **W** and **W'** may be of a height corresponding to the thickness of the floor and ceiling slabs which may also be provided with members extending through these windows for attachment to the columns.

In FIGS. 6 and 7, there are shown modifications of the column structures permitting attachment of wall portions at right angles to one another in addition to the attachment of partitions or horizontal cross members with 60° inclinations. Thus, FIG. 6 shows a column **30** whose closed shell is made up of the webs **2** of four angularly adjoining channel sections **Ba** (described with reference to FIG. 1) whose arms **3** are interconnected by rivets **4a** or bolts **4b**. The closed shell **S'''** of the column **30** is completed by one of the angle members **Bw** whose arm or flange **10** is joined by bolts **31** to the arm **33** of an adjoining channel **Ba** and extends at right angles to the web **11** of this angle member. The arm **12** thereof is affixed by rivets or bolts to the adjoining arm **6** of another channel member **Bi** (described with reference to FIG. 2) whose web **7** thus extends at right angles to the web **11**. The other arm of the channel **Bi** is connected to the arm **33'** of an adjoining channel **Ba** by bolts or rivets. Here, too, the exposed surfaces of the column **30** can be formed by the webs **7** and **11** so that the column may appear to have all of its connecting formations concealed, the members **Bi** and **Bw** here replacing any sheathing or covering layers. When walls are mounted upon the members **33**, **7** and **11**, the column **30** acts as a transition member for converting a 60° framework or skeleton system into a 90° construction. In the modification of FIG. 7, I show another column **40** suitable for use in a 90° system and made up of a profile member **Bi** flanked by and connected to a pair of profile members **Bw**. The column can be closed in a similar manner or can remain open as a channel. In either case, the arms or flanges **10** of the channels **Bw** serve to join connecting elements **14** or **15** to the column in a right-angle system. The connecting elements **14** and **15** may be conventional channels in which glass panes **16** or wall panels **17** are fitted. Sealing gaskets **16'** and **15'** of an elastomeric or synthetic resin material may be used to hold the glass panes and panels in place. This assembly can be used for joining wall means in the same plane or for mounting the wall means at right angles to one another.

The horizontal traverse member **18** of FIG. 8 may be used with the columns illustrated in FIGS. 1-7 and, therefore, in place of the channels **18a** described with reference to FIG. 4. The beam **18** is shown in end section and comprises a pair of juxtaposed strips **19** held together by bolts or rivets **19'** passing through registering bores in these strips. The profiled strips are bent perpendicularly to their respective planes and inwardly to reinforce the strips along their edges and form support surfaces **20** designed to rest upon the columns after insertion through windows or to support slabs or other sheet-like flooring and roofing members. Centrally of the bent marginal portions **21**, I provide a ridge **22** so that the ridges of the juxtaposed strips form a channel or duct designed to stiffen the cross member **18** and to be used for utility purposes. The beam thus is equivalent to an I-beam or a pair of channels in back-to-back relationship whose web is indicated at **23** and whose flanges are reinforced at **21**. While two such bands are shown joined together in the preferred construction of FIG. 8, it will be understood that single bands of this nature, being generally of U-profile, can be employed as horizontal traverses in accordance with the present invention. The bands **19** are, moreover, connected independently of any means joining them to the upright columns.

In FIG. 9, there is illustrated a skeleton of a structure in which columns **1** (made up of profile members **Ba**) and columns **5** (made up of profile members **Bi**) are interconnected at 60° angles by cross beams **18** at the

75

respective flanges. The surfaces 28 of the beams 18 support the ceiling or roofing plates while the surfaces 28a carry the flooring plates. It will be understood, however, that the slabs of triangular configuration described and claimed in my copending application mentioned above can be disposed within the triangular confines formed by the beams 18 so that the surfaces 28, etc. will be coplanar with the corresponding surfaces of these slabs. The roofing and flooring means can include conventional decorative paneling, acoustic surfacing materials and translucent or opaque sheets. Furthermore, such panels and surfacing means can be hung from or mounted upon the cross beams 18 in any conventional manner. As indicated further in FIG. 9, the columns 1, 5 etc. can have portions projecting beyond the lower traverse beams 18 for embedding in the earth or mounting a suitable foundation. If the latter expedient is used, the foundation may consist of a multiplicity of point-like footings for each of the uprights or columns. Alternatively, the traverses 18a can support a roof structure for a basement in which case the footings for the columns will be constituted as pillars or a wall-type foundation arrangement. Foundation plate assemblies as set forth in my copending application are also advantageous for supporting the skeleton shown in FIG. 9.

In FIG. 10, there is shown a slab-like subgroup based upon the junction of members at approximately 60° angles. Such a slab arrangement, using generally triangular concrete plates, can serve to form the ceiling or floor structures retained by the traverses 18 in FIG. 9. In the system of FIG. 10, four trapezoidal frames 25 bearing upon a central hexagonal abutment member 24 are shown provided with respective triangular concrete plates, also in the shape of isosceles trapezoids, while two of these frames are empty of them. Member 24 is spider-shaped and has six outwardly radiating arms 27. It will be understood that the frame 25 for each of the trapezoidal plates can represent the frame defined by the horizontal traverses 18 so that the concrete plates may be emplaced in the plane of the horizontal traverses or cast in these spaces. In the more general case, a slab construction as illustrated in FIG. 10 will merely be mounted upon the surfaces 28 and constructed as described in the copending application. In that case, the abutment or spider 24 may be a member similar to the corresponding column and may be axially aligned therewith for utility purposes or can be constituted by the corresponding column or an extension thereof; this has been shown in FIG. 16 by the dot-dash outlines of several slab portions 25, 26 converging toward the axis of column 1.

The invention described and illustrated is believed to admit of many modifications within the ability of persons skilled in the art, all such modifications being considered within the spirit and scope of the appended claims.

I claim:

1. A structural unit for the joining of wall portions at different angles to one another, comprising an upright column composed of complementary vertical profile members of constant horizontal cross-section each having an upstanding web and a pair of vertical flanges interconnected by said web, and connecting means linking the flanges of adjoining profile member to each other, at least one of said profile members having a first flange adjoining the web thereof at an acute angle and a second flange extending at right angles to the last-mentioned web.
2. A structural unit as defined in claim 1 wherein said acute angle is 30°, said first flange extending radially inwardly, and said second flange extending radially outwardly of the column.
3. A structure comprising a plurality of coplanar horizontal slab portions in the shape of isosceles trapezoids converging toward a common center; and supporting means for said plates including a column composed of complementary vertical profile members of constant horizontal cross-section each having an upstanding web and a pair of vertical flanges interconnected by said web, said profile members being provided with connecting means linking the flanges of adjoining profile members to each other to form radially extending arms receiving said slab portions between them and engaging the converging sides of the trapezoids.
4. A structure as defined in claim 3 wherein said slab portions include trapezoidal frames spanned by trapezoidal concrete plates.
5. A structure as defined in claim 3 wherein said arms extend radially outwardly from the webs of said profile members with uniform mutual separation of 60°.
